UNITED STATES PATENT OFFICE.

DAVID H. TICHENOR, OF NEWARK, NEW JERSEY.

RESERVOIR-WELL.

SPECIFICATION forming part of Letters Patent No. 233,714, dated October 26, 1880.

Application filed August 31, 1880. (No model.)

To all whom it may concern:

Be it known that I, DAVID H. TICHENOR, of the city of Newark, in the county of Essex and State of New Jersey, have invented a new and useful Improvement in Reservoir-Wells, of which the following is a specification.

My invention relates to an improvement in reservoir-wells, and is an improvement upon the well for which I have filed application for 10 Letters Patent under date of August 3, 1880.

The invention described in the said application consisted, primarily, in forming an underground chamber at the bottom of a well of large bore, that the water-supply might be 15 drawn from a great area and drain as large a number of water-veins as possible.

My present improvements consist in applying an air-tight cover to the top of the well-casing for the purpose of forming an air-chamber 20 in which a partial vacuum may be produced, and in drawing off the water at some level below the cover, so as to utilize the space above the water as an air-vessel to ease the operation of the well-pump, while the partial 25 vacuum in the said space produces a greater flow of water from the veins feeding the reservoir through the atmospheric pressure thereby developed upon the sources of the water-supply.

30 My improvement is designed, primarily, to increase the flow of water from the supplying-veins into the well-reservoir, and, secondarily, to ease the working of the pump employed to drain the well by utilizing a portion of the 35 well-casing as an air-chamber.

The first object is at once effected by applying an air-tight cover or partition to the well-casing, either at the top or any convenient point above the surface of the water, and exhausting the air from inside the casing. The 40 second may be effected by introducing the suction-pipe into the well through the side below the cover, or by projecting it downward a suitable distance through the cover, the space 45 above the open end of the pipe in either case serving as an air-vessel to ease the working of the pump.

In the drawings, A is the ground in which the well is excavated by the process described 50 in my former application. B represents a hard stratum near enough to the surface to sustain

the concrete bed D. C is the well curb or casing, composed of sections C', bolted together by flanges f and bolts e. E is the underground reservoir. F is the air-tight cover, shown applied to the top flange of the well e and packed and secured thereto in any desired manner. G is a timber frame to transfer the weight of the curb to the supporting concrete bed D. H is the suction-pipe from the pump, inserted 55 into a socket, I, formed in the side of the curb at a suitable distance below the ground to lead conveniently to the well-pump. J is a pipe leaded into the same socket, and extended downward in the well to the lowest or natural 60 level of the water, (indicated by the line x x.)

It is obvious that if the pump were started with the mouth of the pipe in the water no vacuum or rarefaction of the air in the casing 70 would be produced as long as the water supplied the draft caused by the pump, and as the object of my invention is to employ a vacuum in the casing to stimulate the flow into the reservoir from the water-veins, I must shorten 75 the water-pipe or increase the draft of the pump upon the well.

The former course would prevent the pump from drawing any water whatever in a time of drought, and I therefore increase 80 the demand of the pump upon the well for the purpose of producing a vacuum, and thereby increasing the supply of water to the reservoir and raising the level of the water in the casing.

By forming a hole from one-half to one inch 85 in diameter in the pipe J at any desired point below the range of atmospheric power to lift the water, a vacuum can be maintained without interfering with the pumping operation, even if there should be a leakage of air into the well 90 from any of the joints in the casing. Without this hole to draw a certain amount of air from the well at each stroke of the pump the degree of vacuum produced would only raise the water-level continuously to cover the mouth of 95 the pipe J, and the greatest supply of water to the reservoir would not be secured.

The function of the hole b is to steadily increase the rarefaction of the air in the casing and the flow of water from the veins into the 100 reservoir without interfering with the pumping of water continuously from the well. The flow

of water from the veins may be thus materially increased until the level of the water in the casing is raised by the vacuum therein to a level with the hole *b*, when the rarefaction of the air 5 would cease until such time as the water-level again fell below the point marked *w*, just above the hole *b*.

The space above the line *w* serves as an air-vessel to the well-pump, permitting a free flow 10 of water to the pump at each stroke, which draft is made up by the continuous flow into the reservoir while the pump is reversing or changing stroke.

This mode of increasing the vacuum without 15 shortening the suction-pipe secures all the advantages of an increased flow of water from the supplying-veins, while it obviates the danger of a serious accident to the pump if the end of the pipe were suddenly uncovered and the 20 piston allowed to make a stroke too suddenly.

The use of the concrete (shown at *D* in the drawings) depends upon the existence of hard strata near the surface, upon which the weight of the curb *C* is to be thrown. When such 25 strata exist I employ the concrete to distribute the weight perfectly over a considerable area and to bind the surface together firmly imme-

diate beneath the concrete. The frame *G* is meant to distribute the load over the concrete, but may be dispensed with by making the supporting-flange *e* sufficiently broad. 30

Having thus described my invention, I claim the same in the following manner:

1. In a reservoir-well, the combination, substantially as herein described, of the casing *C*, 35 air-tight cover *F*, and suction-pipe arranged to draw off the water from the casing at some point below the cover, so as to leave an air-space in the top of the casing, substantially as and for the purpose set forth.

2. In a reservoir-well, the combination of a covered casing having a partial vacuum maintained in its upper part, for the purpose described, with a suction-pipe, *J*, extending downward to the natural level of the water, for 40 45 the purpose herein set forth.

In testimony that I claim the foregoing I have hereto set my hand this 19th day of August, A. D. 1880.

D. H. TICHENOR.
